UNITED STATES PATENT OFFICE

129,823

DESIGN FOR A PAPER DRINKING CUP

Oscar G. Reiber, Coatesville, Pa., assignor to Beach & Arthur Paper Co., Indianapolis, Ind.,
a corporation of Indiana

Application February 17, 1941, Serial No. 99,036

Term of patent 7 years

To all whom it may concern:

Be it known that I, Oscar G. Reiber, a citizen of the United States, residing at Coatesville, in the county of Chester and State of Pennsylvania, have invented a new, original, and ornamental Design for a Paper Drinking Cup, of which the following is a specification, reference being had to the accompanying drawing, forming part thereof.

The figure is a perspective view of a paper drinking cup, showing my new design.

I claim:

The ornamental design for a paper drinking cup, as shown.

OSCAR G. REIBER.
